UNITED STATES PATENT OFFICE

JOHN D. SPALDING, OF CRAFTON, PENNSYLVANIA, ASSIGNOR, BY MESNE ASSIGNMENTS,
TO THE NATIONAL SUPPLY COMPANY, OF TOLEDO, OHIO, A CORPORATION OF OHIO

ROTARY WELL-DRILLING MACHINE

Application filed February 18, 1926. Serial No. 89,058.

This invention relates to rotary well drilling machines and more particularly to a rotary machine of the small universal type of such machines, embodying the feature of construction required by the demands of certain oil fields where large rotary machines are not needed.

Rotary well drilling machines as now constructed and used are, for the most part, expensive and of comparatively large and heavy construction and are designed to handle large casing and pipe and to drill to great depths, for example, 7,000 feet or over. This work requires a rotary machine to be designed so as to support great weights during the drilling operations. Many fields in which oil has been found do not require that the wells be drilled to such extreme depths nor that the well holes be of such large diameters since the oil is found in these fields in relatively shallow sands or reservoirs.

It is therefore an object of this invention to provide a rotary well drilling machine particularly adapted and designed for use in such fields where the drilling to great depths is not required and in which casings of relatively small diameter are used, it being essential in such rotary machines that they be of compact construction, self-contained and easily removed from location to location and require a minimum of labor in setting up or taking down.

Another object of this invention is to provide a rotary well drilling machine in which means are provided by which the spider may be selectively engaged with the rotary table or the rotary table base solely by vertical movement of the spider and rotation thereof without the use of dogs, latches or the like.

Another object of this invention is to provide a rotary well drilling machine with independent sets of pockets in the rotary table and non-rotatable base respectively and a spider having a single set of lugs adapted to be selectively engaged with either of the sets of pockets in order to provide a universal "make and break" rotary.

Another object of this invention is to provide a self-contained rotary well drilling machine with a unitary base, carrying both the

table and driving mechanism, the table being driven by a unit pinion shaft assembly embodying a sturdy one piece bearing housing equipped with heavy duty roller bearings and adjustable to compensate for wear. 55 This construction results in a very compact, sturdy, self-contained machine providing in connection with the pinion shaft assembly of an outboard sprocket, thus permitting easy alignment with the rotary draw-works. 60

Another object of this invention is to provide a rotary well drilling machine of the character above described in which the sprocket may be easily removed from the shaft. 65

Another object of this invention is to provide a rotary well drilling machine in which a lubricating reservoir is provided for lubricating from the said reservoir by the aid of centrifugal force the table ball-bearings and 70 hold-down bracket bearings when the machine is in operation.

Another object of this invention is to provide a rotary well drilling machine in which the cylindrical opening through the rotary 75 table is provided with slots to permit the use of fish-tailed bits or the like of larger size than the diameter of the central cylindrical opening through the table.

Another object of this invention is to provide a rotary well drilling machine in which locking means are provided for locking the spider to the table to prevent vertical movement of the spider relative to the table. 80

Another object of this invention is to provide a rotary well drilling machine in which the rotary table may be selectively locked to the base to prevent movement of the table relative to the base. 85

Another object of this invention is to provide a rotary well drilling machine in which a spider is provided that may be employed to drive either the drill stem bushing directly or through the medium of split table bushings. 90

Other objects and advantages of this invention will be apparent from the following detailed description of a preferred embodiment thereof as illustrated in the accompanying drawings, in which drawings: 95 100

Figure 1 is a top plan view of a rotary machine embodying this invention.

Figure 2 is a side elevation thereof mainly in vertical mid-section and taken substantially on the line 2—2 of Figure 1.

Figure 3 is an enlarged top plan view of a rotary table embodied in this invention, illustrating the vertically movable spider partially in horizontal section and illustrating a split bushing supported within the spider and locked thereto.

Figure 4 is a similar fragmental top plan view of a rotary table embodied in this invention, illustrating the same as within the spider in position with the split bushing removed and illustrating the relative positions of the sets of pockets provided in the rotary table and rotary table base and the set of lugs formed on the spider engaged within the said pockets provided in the rotary table.

Figure 5 is a similar fragmental top plan view of the rotary table embodied in this invention, illustrating the spider as in position to move vertically so that its lugs will pass between the spaces formed between the pockets formed in the central bore of the rotary table.

Figure 6 is a diagrammatic top plan view of a portion of the table base, illustrating the slots formed in the table base at diametrically opposed points of the bore through the table base so as to permit the use of fish-tailed bits and the like of a diameter greater than the diameter of the said bore.

Figure 7 is an enlarged fragmental side elevation mainly in vertical section, illustrating the lubricating means provided for lubricating the hold-down bearings from a reservoir by the aid of the centrifugal force exerted on the oil in the reservoir and also illustrating the latch means provided to prevent rotary movement of the table relative to the base.

In the preferred embodiment of this invention illustrated in the accompanying drawings, A illustrates a rotary base unit which base unit supports a rotary table unit B, a bushing unit C, either through the table unit B or directly, and supports also a driving unit D which drives the rotary table unit B. In the rotary table unit B a lubricating unit E is provided.

The rotary table base unit A is preferably of the following construction and comprises a table base 1 which is usually supported on and secured to skids 2. The base 1 is a casting having an upwardly extending annular portion 3. The portion 3 provides a bearing race in which annular race rings 4 are mounted. The upwardly extending portion 3 of the base 1 also provides an annular guide shoulder 5 which guides the rotary table unit B. A bore 6 is formed through the base unit 1 and slots 7 are formed at diametrically opposed points in the bore 6 so as to permit the

use of fish-tailed bits or the like which are of greater width than the diameter of the bore 6. Secured to the base 1 is a hold-down bracket 8 which provides a hold-down bracket bearing 9. A set of diametrically opposed spaced pockets 10 are formed in the base 1 and are adapted to receive correspondingly spaced and diametrically opposed lugs 11 which are formed on the spider 12 of the bushing unit C.

The rotary table unit B is preferably of the following construction and comprises a gear table 13 having an annular drive gear 14 formed on its under surface 15 and which annular driving gear 14 is adapted to mesh with a driving pinion gear 16 of the driving unit D. A central bore 17 is formed through the rotary table unit B directly over the bore 6 of the rotary base unit A. A downwardly extending annular portion 18 of the gear table 13 provides a bearing race in which annular race rings 19 are positioned, the annular race rings 19 being complementary to the annular race rings 4 and ball bearings 20 are mounted between the two sets of annular race rings. A cylindrical extension 21 extends below the portion 18 and co-operates with the annular shoulder 5 of the table base 1 to guide the rotation of the table 13. An upwardly extending rim 22 is formed on the table base 1 and fits within an annular recess 23 formed in a downwardly extending rim 24 formed on the table 13 to provide an oil and mud seal. An annular flange is formed on the gear table 13 which provides a shoulder 25 which co-operates with the hold-down bracket bearing 9. Formed in the bore 17 of the gear table 13 are a set of diametrically opposed and spaced pockets 26. The pockets 26 are formed in inwardly projecting segmental lugs 27 which project into the bore 17 of the gear table 13. The said lugs 27 are spaced apart so as to provide passages 28 between the said lugs 27 so that the lugs 11 formed on the spider 12 may pass through the passages 28 to be engaged in the pockets 10 of the table base 1. The lugs 11 formed on the spider 12 are also adapted to be engaged with the pockets 26 and the lugs 11 are engaged either in the pockets 26 of the gear table 13 or in the pockets 10 of the base 1 solely by vertical movement of the spider 12 and rotation thereof to align the lugs 11 with the respective pockets.

The bushing unit C is preferably of the following construction and comprises the spider 12 which is a cylindrical casting or forging having a central bore 29 formed therethrough and having a set of lugs 11 formed at diametrically opposed and spaced points around its periphery at or near the lower end thereof. The cylindrical casting or forging forming the spider 12 has an inner bore 29. The upper portion of the bore consists of a cylindrical portion 36 having a

recess 36^a and a shoulder 36^b. The lower portion of the bore is tapered as illustrated at 30 to receive tapered split table bushings 31. The tapered split table bushings 31 are tapered on their inner bore as illustrated at 32, adapted to receive drill stem split bushings 33. The tapered table bushing 31 has ears 31^a complementary to the recess 36^a of the spider 12. The split drill stem bushing 33 is provided with an annular shoulder 34 which is adapted to extend above the upper end surface of the bushing 31. This shoulder is provided with ears 34^a complementary to the recess 36^a of the spider 12. By this means 15 the split drill stem bushing 33 is driven directly from the spider 12 and not through the agency of the split table bushing as is usually the case.

The drive unit D is preferably of the following construction and comprises a sleeve 37 having outwardly extending clamp portions 38 which are secured to the table base 1 by any suitable means, such as the bolts 39. The sleeve 37 provides a housing for the pinion shaft bearings 40 upon which the pinion shaft 41 is mounted. The pinion shaft 41 is keyed to the pinion gear 16. The bearings 40 are roller bearings and are maintained against endwise motion by means of 20 the bearing sleeve 42 and the end-plate 43 at one end of the sleeve 37 and by means of washers 44 at the opposite end of the sleeve 37, the washers 44 being interposed between the face of the pinion gear 16 and the shoulder formed by the end of the sleeve 37. The drive sprocket 45 is keyed to the pinion drive shaft 41 and is securely held in position by means of a cap 46 which is secured to the end of the pinion shaft 41 by means of a cap-screw 47. A bearing bushing 48 is interposed between the end-plate 43 of the sleeve 37 and the inner face of the drive sprocket 45. By this assembly, the entire drive unit D may be 25 disassembled with ease when it is desired to replace or repack the bearings 40 or when it is desired to replace or repair the pinion gear 16 and it is a simple matter to remove the drive sprocket 45 when the same becomes worn and it is desired to 30 replace the same. Mounted within bores formed in the sleeve 37 are grease fittings 49 which are preferably of the ball check valve type so that a grease gun may be fitted thereto and the bearings greased with ease. The fittings 49 are protected from mud by the caps 50 screw-threaded into the sleeve 37. In order to take up the wear on the thrust-bearing washers 44, shims 71 are provided between the end-plate 43 and the end face of the sleeve 37. The removal of a portion of these shims 71 permits the moving in of the plate 43 and bearing 40, bearing sleeve 42 and the opposite end bearing 40 to 35 compensate for wear on the bearing washers 44.

The lubricating unit E is preferably of the following construction and comprises a reservoir 51 which is formed in the gear table 13 and is provided at its upper end with a cap 52. A tube 53 having a central bore therethrough is screw-threaded into the gear table 13 at the bottom of the reservoir 51. Laterally extending ports 54 are formed in the upper end of the tube 53 and are what is termed overflow ports through which the lubricant from the reservoir passes outward to lubricate the balls 20 and the hold-down bearings 9. Laterally extending ports 55 being provided in the tube 53 at a position near the lower end of the reservoir 51, which ports communicate with a port 57 formed in the gear table 13 and through the lower portion of the base of the tube 53 to a passway 72 formed in the race in which the annular race rings 19 are mounted. Waste or like material may be mounted in the reservoir 51 and the same saturated with lubricating oil, grease or the like. On rotation of the gear table 13, centrifugal force will tend to throw the lubricant from the reservoir 51 through the ports 55 and bore of the tube 53 and through the port 57 and passage 72 to the respective bearing. The balls 20 will be initially lubricated or flooded directly from the reservoir 51 through the port 57.

In order to prevent relative movement between the table base 1 and the gear table 13, a manually operable latch 58 is provided which passes through a bore 59 formed in the cylindrical extension of the gear table 13.

A latch 60 is provided which is easily operated for securing the spider 12 in either the "break out" or drilling positions. The latch 60 is mounted within a recess 61 formed in the gear table 13 and comprises a stud 62 upon which an eccentric latch member 63 is mounted so that when the stud 62 is rotated, the eccentric latch member 63 will project through a recess formed in the inner face of the gear table 13 and into a recess formed in the periphery of the spider 12. The stud 62 is slideable through the latch member 63 and in order to prevent withdrawal of the stud 62, a pin 64 is mounted at the lower end thereof. The stud 62 is grooved throughout its length and the bore of the latch member 63 has an inwardly projecting key which fits into the groove formed in the stud 62. A head 65 is formed in the upper end of the stud 62 and is provided with an indicating arrow 65^a which indicates whether the latch 60 is in the latched or open position. The head 65 fits within an enlarged recess formed in the upper surface of the gear table 13 so that its top face will be practically flush with the face of the gear table 13 so that on rotation of the gear table 13, the head 65 will not be apt to become engaged with any tools or the feet or the like of the operator or operators of the rotary machine.

5 The drill stem bushing 33 is provided with a laterally extending groove 66 in which a bar latch member 67 is mounted and which bar latch member 67 has an upwardly extending pin 68 secured thereto which passes through an elongated slot 69 formed in the upper face of the drill stem bushing 33. A recess 70 is formed in the spider 12 in position to receive the end of the bar latch member 67. On rotation of the drill stem bushing 33, the bar latch member 67 in the groove 66 is thrown outward by centrifugal force so that the same will be engaged within the recess 70 formed in the spider 12.

10 15 From the foregoing, it will be apparent that I have provided a rotary well drilling machine of the universal type that is a small unit construction and may be easily installed in position within a well derrick and so installed that the drive sprocket 45 may be easily aligned with the rotary draw-works (not shown) and which rotary well drilling machine is of such construction that the same may easily be removed from position within 20 the well derrick and loaded upon a truck or other vehicle and conveyed to any point of use and that my universal rotary well drilling machine need not be of heavy or expensive construction but that the same is extremely simple and well adapted to perform the functions for which it is constructed.

25 Having fully described a preferred embodiment of this invention, it is to be understood that I do not wish to be limited to the exact details herein set forth which may obviously be varied without departing from the spirit of my invention as set forth in the appended claims.

I claim:

30 40 1. A rotary well drilling machine comprising a table base, a rotary table mounted on the base and provided with a central bore, a spider positioned in the bore and having a single set of lugs, said lugs being adapted to be engaged either with the table or with the base, the engaging of the lugs with the base or table being accomplished solely by movement of the spider.

45 50 55 60 2. A rotary well drilling machine comprising a table base, a rotary table mounted on the base and provided with a central bore, a set of diametrically opposed pockets formed in the said bore, a set of diametrically opposed pockets formed in the said base, a spider mounted in the bore and having a set of diametrically opposed lugs formed on the spider and adapted to be engaged with either the pockets in the table or the base, the engaging of the said lugs with the table or the base being accomplished solely by movement of the said spider.

65 3. A rotary well drilling machine comprising a table base, a rotary table mounted on the base and having a central bore, a plurality of spaced pockets formed in the bore of

the said table, a plurality of equally spaced pockets formed in the base, a spider mounted in the said bore and having a plurality of lugs spaced on its periphery so as to correspond with the spacing of the said pockets, the said lugs being adapted to be engaged with either the pockets in the table or base, said engagement of the lugs with either of said table or base pockets being accomplished solely by movement of the said spider. 70

75 4. A rotary well drilling machine comprising a table base, a rotary table mounted on the base and having a central bore, a plurality of spaced pockets formed in the bore of the said table spaced to provide passages, a plurality of equally spaced pockets formed in the base, a spider mounted in the said bore and having a plurality of lugs spaced on its periphery so as to correspond with the space of the said pockets, the said lugs being adapted to be engaged with either the pockets in the table or base, said engagement of the lugs with either of the said table or base pockets being accomplished solely by movement of said spider, and the said lugs being adapted to pass through the passage formed between the pockets formed in the bore of the said table. 80

85 5. A rotary well drilling machine comprising a table base, a rotary table mounted on the base and having a central bore, a plurality of spaced segmental lugs formed in the bore of said table and providing spaced pockets in the bore of the said table, a plurality of equally spaced pockets formed in the base, a spider mounted in the said bore and having a plurality of lugs spaced on its periphery so as to correspond with the spacing of the said pockets, the said lugs being adapted to be engaged with either the pockets in the table or the base, said engagement of the lugs with either of said table or base pockets being accomplished solely by vertical movement and rotation of the said spider. 90 95

100 105 6. A rotary well drilling machine comprising a table base, a rotary table mounted on the base and having a central bore, a plurality of spaced pockets formed in the said bore near the lower end thereof, a plurality of equally spaced pockets formed in the base, a spider mounted in the said bore and having a plurality of lugs spaced on its periphery near the lower end thereof so as to correspond with the spacing of the said pockets in the bore of the table, the said lugs being adapted to be engaged with either the pockets in the table or the base, said engagement of the lugs with either said table or base pockets being accomplished solely by vertical movement and rotation of the said spider. 110 115 120

125 7. In a rotary well drilling machine, the combination of a base, a rotary table supported on bearings on the base, a hold-down bracket bearing between the base and the table, a lubricating reservoir formed in the ta- 120

- ble, ports formed in the table and extending from the reservoir to said bearings and adapted to convey the lubricant from the reservoir to the said bearings with the aid of centrifugal force when the said table is rotated and
- 5 means for rotating said table.
8. In a rotary well drilling machine, the combination of a base, a rotary table supported on bearings on the base, a hold-down bracket bearing between the base and the table, a lubricating reservoir formed in the table, an overflow pin mounted in the said reservoir and provided with a central bore through which lubricant from the reservoir overflows to the said bearings, ports formed
- 10 in the table and extending from the reservoir to the said bearings, the said ports being adapted to convey lubricant from the reservoir to the said bearings with the aid of centrifugal force when the said table is rotated
- 15 and means for rotating said table.
- 20

In testimony whereof I affix my signature.
JOHN D. SPALDING.
